UNITED STATES PATENT OFFICE.

HENRY TILL, OF LOS ANGELES, CALIFORNIA.

COLLAR-SUPPORT.

983,954.

Specification of Letters Patent. Patented Feb. 14, 1911.

Application filed December 28, 1909. Serial No. 535,368.

To all whom it may concern:

Be it known that I, HENRY TILL, citizen of the United States, residing at Los Angeles, in the county of Los Angeles and 5 State of California, have invented certain new and useful Improvements in Collar-Supports, of which the following is a specification.

This invention relates to collar supports 10 and has for its object to provide a comparatively simple and inexpensive device of this character especially designed for attachment to ladies' lace or fabric collars and to the collars of men's soft shirts for the purpose of 15 retaining the collar in proper shape and preventing sagging of the same when in position on the neck of the wearer.

A further object is to provide a collar support formed of a piece of thin wood or 20 other suitable material having a reinforcing strip on one side thereof and a yieldable backing on the other, said reinforcing strip being formed of open mesh fabric saturated with an adhesive material, the latter serving 25 the dual function of securing the reinforcing strip to the body of the collar support and also as a means for securing said support in position on a collar.

Further objects and advantages will appear 30 in the following description, it being understood that various changes in form, proportions and minor details of construction may be resorted to within the scope of the appended claims.

For a full understanding of the invention 35 and the merits thereof and also to acquire a knowledge of the details of construction and the means for effecting the result, reference is to be had to the following description and 40 accompanying drawings, in which:

Figure 1 is a perspective view of a support constructed in accordance with my invention, showing the same applied to a collar; Fig. 2 is a vertical sectional view of the 45 collar showing the manner of securing the support thereto; Fig. 3 is a detail perspective view of the support detached; Fig. 4 is a transverse sectional view taken on the line 4—4 of Fig. 3; Fig. 5 is a perspective view 50 showing the body portion, yieldable backing and reinforcing strip separated; Fig. 6 is a perspective view illustrating a modified form of the invention; Fig. 7 is a transverse sectional view taken on the line 7—7 of Fig. 6;

Fig. 8 is a perspective view showing the support made in continuous length; Fig. 9 is a perspective view showing the support used in connection with a collar of a soft shirt.

Corresponding and like parts are referred to in the following description and indicated 60 in all the views of the drawings by the same reference characters.

The improved collar support forming the subject matter of the present invention comprises a body portion 5 preferably formed of 65 a strip of thin wood of sufficient rigidity to retain the collar in proper shape, while at the same time permitting the strip or body portion to yield slightly when bending or turning the neck.

Secured to one side of the body portion 5 is a reinforcing strip 6, preferably formed of cheesecloth, muslin or other open mesh fabric, said reinforcing strip being saturated with blue or other adhesive material, the 70 glue being held in suspension in the mesh of the fabric and serving the dual function of securing the reinforcing strip to the body portion 5 and also as a means for securing the support in position on a collar. The 75 adhesive material with which the reinforcing strip 6 is saturated consists of a compound of white glue, paraffin, glycerin and water, such a compound having been found, by experience, especially desirable for this 80 purpose inasmuch as it is white in color to match the color of most shirt waists and collars, and, to a certain extent, moisture proof, thus guarding against coming loose when subjected to perspiration from the 85 neck of the wearer, the glycerin in the compound preventing easy breakage or snapping of the support. The compound is rendered adhesive by the application of heat and moisture and soluble in warm water. 90

Secured to that side of the body portion 5 opposite the reinforcing strip, is a backing strip 7, preferably formed of canton flannel although felt or other yieldable material will answer just as well. The yieldable backing 100 strip 7 is adapted to bear against the neck of the wearer so as to prevent the body portion 5 from coming in contact with the skin and cutting or otherwise lacerating the same. If desired, the backing strip 7 may 105 be extended laterally beyond the edge of the body portion 5 to form a yieldable flange 8 to assist in preventing the longi-

tudinal edges of the body portion 5 from pressing against the skin when the neck is turned.

It is preferred to make the collar supports in predetermined lengths with the opposite ends thereof rounded at 9, but if desired the collar supports may be made in the form of a continuous strip and subsequently cut or severed into the desired length 10 to fit the collars to which they are applied, as best shown in Fig. 8 of the drawings.

In using the device, the strips are applied to the inner face of a collar, either by moistening the reinforcing strip 6 and pressing 15 the support laterally against the collar with a heated iron, or by moistening the collar and pressing a heated iron on the support, thus firmly securing the support in position on the collar and preventing 20 sagging of the same when in use.

It will here be noted that when the collar is immersed in water to effect the washing thereof, the warm water will dissolve the adhesive material on the reinforcing strip 25 and thus cause the support to drop off and any particles of glue or adhesive material left on the collar will be dissolved in the warm water so as not to injure the fabric.

In Fig. 9 of the drawings, the support is 30 shown of angular formation, such a construction of support being especially desirable for attachment to the collars of men's soft shirts in order to retain the collar in proper shape, making unnecessary the work 35 of buttoning down the points of the collar. The angular supports 10 shown in Fig. 9 of the drawings are applied to the collar 11 of a shirt in the same manner as the supports shown in Fig. 1. If desired however, 40 straight supports of the construction shown in Fig. 3 of the drawings may be used on

the collars of men's soft shirts in place of the angularly disposed supports shown in Fig. 9 of the drawings.

The device is extremely simply in construction and may be manufactured and placed on the market at a relatively small initial cost.

Having thus described the invention, what is claimed as new is:

1. A collar support including a flat relatively thin body portion, a yieldable backing secured to one side of the body portion, and a reinforcing strip secured to the other face of the body portion and formed of open mesh fabric saturated with a mucilaginous compound to present oppositely disposed adhesive faces, said compound serving to retain the reinforcing strip on the body portion and also serving to secure the support 60 in position on a collar.

2. A collar support comprising a body portion having an angular terminal, a yieldable backing secured to one side of the body portion and covering said angular terminal, 65 a reinforcing strip secured to the other side of the body portion and also covering the angular terminal, said reinforcing strip being saturated with a mucilaginous compound to present oppositely disposed adhesive faces for contact with the body portion and a collar, respectively, said compound being rendered soluble in water and adhesive under the application of heat and moisture.

In testimony whereof I affix my signature in presence of two witnesses.
